UNITED STATES PATENT OFFICE

2,300,500

BOX FOR PACKING LAMP SHADES

David J. Gorelick, Chicago, Ill., assignor to Sandel Manufacturing Company, Chicago, Ill., a corporation of Illinois

Application December 30, 1940, Serial No. 372,368

10 Claims. (Cl. 206—65)

This invention relates to a method and means for packing merchandise, as for storing and shipping, and more particularly to a package whereby a plurality of lamp shades or similar articles may be packed safely and compactly for storage or shipping without possibility of breakage, and a method of utilizing same.

The primary object of this invention is to provide a new and improved package for lamp shades or the like articles in which a plurality of lamp shades will be nested one within the other in a safe and compact manner.

A further object of this invention is to provide a new and improved package for lamp shades or the like in which the lamp shades will be held within an enclosing body and against lateral motion thereof.

A further object of this invention is to provide a novel and improved package for packing lamp shades in which the lamp shades or similar articles will be prevented from moving either longitudinally or laterally.

A further object of this invention is to provide a novel and improved package for lamp shades in which the lamp shades or similar articles will be supported within an enclosing body nested within one another, but each being suspended by means of its spider.

A further object of this invention is to provide a novel and improved method of packing lamp shades which comprises suspending the lamp shades within an appropriate packing enclosure so that same are spaced from one another and supported by their respective spiders.

A further object of this invention is to provide a novel and improved method for packaging lamp shades which will be simple in its steps and require a minimum of apparatus and labor.

A further object of this invention is to provide a novel and improved package for lamp shades and the like which will provide means whereby the lamp shades are supported within a packing enclosure nested in spaced relation to one another.

A further object of this invention is to provide a novel and improved package for packing lamp shades in which a maximum of lamp shades can be packed into a minimum of space and in a safe and expedient manner.

A further object of this invention is to provide a package for lamp shades which will comprise a minimum of easily formed and assembled parts and which will result in a highly efficient package.

With the foregoing and other objects in view which will appear as the description proceeds, the invention of certain novel features of construction, arrangement and combination of parts, 5 procedures, modes and steps of practice herein-after fully described, illustrated in the accompanying drawing, and particularly pointed out in the appended claims, it being understood that various changes in form, proportion, size and 10 minor details of structure, and in details of procedure of the method may be made without departing from the spirit or sacrificing any of the advantages of the invention.

For the purpose of facilitating an understanding of my invention, I have illustrated in the accompanying drawing a preferred embodiment of the apparatus thereof from an inspection of which, when considered in connection with the following description, my invention, its mode of 15 construction, assembly, operation and practice, and many of its advantages should be readily understood and appreciated.

Referring to the drawing in which the same characters of reference are employed to indicate 20 the corresponding or similar parts throughout the several figures of the drawing:

Fig. 1 is a perspective view of a completed package of lamp shades formed in accordance with 25 my invention.

Fig. 2 is a vertical sectional view taken generally along the line 2—2 of Fig. 3.

Fig. 3 is a sectional view taken along a horizontal plane through the package as indicated by the line 3—3 of Fig. 1.

Fig. 4 is an elevational view of a member 30 adapted to be used with my invention.

Fig. 5 is an elevational view of another member adapted to be used with my invention.

Generally the invention consists of supporting 35 a plurality of shades by means of their respective spiders, spaced from one another and nested within one another in an appropriate packing enclosure by means of a plurality of columns extending between a pair of opposed faces of said packing enclosure.

Referring to the figures, the reference character 10 designates generally a packing case or carton which is entirely conventional in formation 40 and which consists of four side walls 11, 12, 13 and 14, and two end walls. The bottom end wall is designated as 15 and is formed in the same manner as the upper end wall 16, namely by the association of flaps similar to 17, 18, 19 and 20, 45 as shown. The carton is formed as a blank of

pasteboard and is usually assembled by means of tape 21 or the like appropriately placed adhering to the carton.

Figs. 2 and 3 are sectional views taken through a completely enclosed carton ready for packing or shipping. A cushioning platform or spacer 22 is provided at each end of the carton. Said spacers each consist of a horizontally disposed rectangular member 23 formed of pasteboard or the like and adapted to fit snugly within the four walls 11, 12, 13, and 14 of the carton. The edges of the members 23 are provided with downwardly or upwardly extending flanges, as the case may be, for spacing the members 23 from either the upper end wall 16 or from the lower end wall 15. The flanges are designated 24, 25, 26 and 27. The flanges of the upper member 23 extend upwards to space that member from the end wall 16, while the flanges of the lower member 23 depend downwards for spacing that member from the lower end wall 15.

It should be appreciated that each of the members 23 is identical in construction, the only difference between them being in their final disposition within the structure, that is, reversed one from the other.

Each of the members 23 has a plurality of V-shaped slots 28 formed therein for a purpose to be presently described. In the embodiment shown, three of such slots 28 are provided the vertical median axis of each of the V's being arranged substantially perpendicular to each of three radial lines extending outwardly from the geometric center of the member 23 and spaced 120° apart. The slots 28 are all equidistant from the center of the member 23 and generally have the apices at approximately the intersection of their median axes and the above referred to radial lines. This arrangement will be clearly understood by reference to Fig. 3.

Each of the slots 28 of the lower member 23 is provided with a V-shaped elongated member 29 of pasteboard or the like having its arms inserted into the arms of the V-shaped slot 28, a portion thereof extending downward to contact the inner face of the wall 16, the remainder thereof extending upwards of the member 23. The length of such member 29 is identical with the inner dimension of the carton 10 from inner face of end wall 16 to inner face of end wall 15, so that the finally completed carton will have three columns 29 extending from end wall to end wall and preventing inward movement of said end walls. Obviously, the elongated members 29 are intended to engage with the slots 28 provided in the upper member 23, the upper cushioning spacer 22 being so arranged that the slots 28 thereof will line up with the slots of the lower cushioning member 22.

The member 29 is preferably formed of a rectangular sheet of cardboard, such as shown in Fig. 4, adapted to be folded along the center line 30 thereof to conform to the required shape adapted to engage within the slots 28. The member 29 is provided intermediate its ends with a plurality of transverse slots 31 equally spaced from one another and arranged closer to one end of the member 29 than the other. In assembling the member 29 within the carton, these slots 31 are intended to be closer to the upper end of the carton 10.

The type of lamp shade that is intended to be packed within my new package is generally indicated in the drawing as shown. Each of the shades designated generally 32 comprises a

translucent or otherwise body portion 33 in the form of a truncated conical shape, having a lower wire frame edge 34 and an upper wire frame edge 35. Each of the upper wire frame edges 35 is provided with a three-armed spider 36 having the free ends joined to the upper wire frame edge 35 and the common points joined by means of an annular ring 37. The jointures are formed by soldering, bending, welding, or any other means not material to the invention. However, the spiders 36 are intended to be the means by which the shades 33 are supported upon their respective lamps. Likewise, I utilize the spider 36 of each of the shades 33 as the means whereby the shade may be supported or positioned within the packing carton or enclosure 10. In view of this, it is obvious that my invention may be utilized with any type of shade or similar device which is provided with a spider or similar means adapted to slip into the slots 31 as will be presently explained.

In assembling the package, the carton 10 is assembled in the usual manner with the aid of the adhesive tape 21, the bottom wall 15 being closed, but the upper end wall 16 remaining open with the flaps unsealed. Following this, a cushioning member 22 is inserted into the carton 10 with the depending flanges 24, 25, 26 and 27 extending downwards. This is pushed into position to the lowest point within the carton so that the lower member 23 is spaced from the bottom wall 15. The cushioning platforms 22 may have been pre-formed or may consist of flat blanked members adapted to be bent to shape as is familiar to those skilled in the carton making art.

Following this, the members 29 are each folded from their flat blank form along the lines 30 to the final V formation and inserted into the slots 28 of the member 23 with the transverse slots 31 positioned closer to the upper end 16 of the carton 10. In the illustrated embodiment, as has been explained, there are three of these elongated members 29 and they form vertically extending columns within the carton.

The next step in the assembly of the package consists of placing the shades 33 in position upon the columns or member 29. The dimensions of the box have been chosen so that each of the walls 11, 12, 13 and 14 will engage the peripheral edge of the lamp shades 32 and thereby limit lateral movement thereof. The first shade is slipped into the carton and moved downwardly therein with its largest end formed by the wire frame edge 34 going down first. The columns 29 each will pass through one of the spaces formed between the arms of the spider 36, free downward movement of the lamp shade 32 thus being unobstructed. When the lowermost slot 31 of the columns has been reached, the lamp shade is twisted in a counterclockwise direction as viewed in Fig. 3. In the folding of the member 29 from its flat form to its V formation, the slots 31 become as notches along the apex of the V-shaped column; hence, each of the arms of the spider 36 will engage into one of these notches 31 and be held therein against transverse movement. As to lateral movement same is prevented by the walls 11, 12, 13 and 14 of the carton. If desired, the height of the notch or slot 31 which is intended to carry the lowermost lamp shade of the carton may be chosen of such height above the platform cushion 22 that the lowermost edge of said lamp shade 32 rests upon the member 23. If desired otherwise, the notch may be chosen so

that the lowermost lamp shade is spaced above the member 23.

In like manner, each of the lamp shades is lowered into the carton 10 over the columns 29 and twisted into its respective group of notches or slots 31 provided therefor in said columns. The notches are spaced so that each of the lamp shades 32 is spaced above the other and so that none of the bodies 33 contact one another.

The carton 10 may be constructed of any suitable length and to hold as many lamp shades 32 as desired. The illustrated carton is designed to hold eight of such shades. After the eighth shade 32 has been positioned in its respective trio of notches 31, a cushioning member 22 is inserted thereon and having the flanges 24, 25, 26 and 27 extending upwards so that the member 23 will be spaced from the upper wall 16. After the cushioning spacer 22 is in position, elongated rod members 38, one of which is shown in Fig. 5, is poked down into the triangular spaces formed between each of the spider arms of the respective shades 32 and the apex of the V-shaped member with which same is associated. The members 38 extend the entire length of the carton and each has a bent portion 39 at the upper ends thereof to aid in the manipulation of same. Obviously the purpose of the rod members is to prevent rotative motion of the shades upon the columns 29 to cause same to drop out of their respective notches or slots 31.

With the members 38 finally in place, the flaps 17, 18, 19 and 20 may be fastened in position in the well known manner and the carton or package of lamp shades is complete for packing or shipping.

It should be apparent that each of the lamp shades 32 is completely suspended within the carton, is protected from injury caused by contact with other lamp shades or any of the packing means, is positively held within the carton and prevented from moving in any direction.

It should also be apparent from the above description that the columns upon which the shades are disposed bear against opposite ends of the carton 10 and thereby act as compression members preventing collapse of the carton as may be possible if a great many of such cartons are piled one atop another.

By my new method and means it is possible to more quickly assemble the package than theretofore possible, and it is more economical since all excelsior, and other protective wadding or packing or paper has been eliminated.

It is believed that my new invention, its mode of construction and assembly, its practice and procedure, and many of its advantages should be readily understood from the foregoing without further description, and it should also be manifest that while a preferred embodiment has been shown and described for illustrative purposes, the structural details and the steps of practice are capable of wide variation within the purview of my invention as defined in the appended claims.

What I claim and desire to secure by Letters Patent of the United States is:

1. In a package for lamp shades, each having radial spider arms, an enclosing body having a pair of opposed end walls, a plurality of elongated columns each extending between said opposed end walls and adapted to pass through the spaces defined by the spider arms of each shade, each of said columns being similarly provided with a plurality of spaced slots, a similarly positioned slot of each of said columns being adapt-

ed to engage a spider arm of a single lamp shade and suspend same within said enclosure upon said columns spaced from an end wall thereof.

2. In a package for lamp shades, each having radial spider arms, an enclosing body having a pair of opposed end walls, a plurality of elongated columns each extending between said opposed end walls and adapted to pass through the spaces defined by the spider arms of each shade, each of said columns being similarly provided with a plurality of spaced slots, a similarly positioned slot of each of said columns being adapted to engage a spider arm of a single lamp shade and suspend same within said enclosure upon said columns spaced from an end wall thereof, and means for locking said spider arms in said engaged position.

3. In a package for lamp shades, each having radial spider arms, an enclosing body having opposed end walls, a plurality of rigid columns extending between said end walls and adapted to pass between the spaces defined by said spider arms, each of said columns having at least one corner in cross section and presenting same in the same circular direction about said enclosing body, each column being provided with similarly positioned transverse slots spaced therealong, whereby each of said lamp shades may be moved into slots at a single level and be engaged thereby and suspended upon said columns within said enclosing body.

4. In a package for lamp shades, each having radial spider arms, an enclosing body having opposed end walls, a plurality of rigid columns extending between said end walls and adapted to pass between the spaces defined by said spider arms, each of said columns having at least one corner in cross section and presenting same in the same circular direction about said enclosing body, each column being provided with similarly positioned transverse slots spaced therealong, whereby each of said lamp shades may be moved into slots at a single level and be engaged thereby and suspended upon said columns within said enclosing body, and means associated with said columns preventing the spider arms for moving out of said slots.

5. In a package for lamp shades, each having radial spider arms, an enclosing body having opposed end walls, a plurality of rigid columns extending between said end walls and adapted to pass between the spaces defined by said spider arms, each of said columns having at least one corner in cross section and presenting same in the same circular direction about said enclosing body, each column being provided with similarly positioned transverse slots spaced therealong, whereby each of said lamp shades may be moved into slots at a single level and be engaged thereby and suspended upon said columns within said enclosing body, and means associated with said columns preventing the spider arms from moving out of said slots comprising an elongated member passing through each column longitudinally thereof, between the spider arms and the corner of said column.

6. In a package for lamp shades, each having radial spider arms, an enclosing box body having end walls, a cushioning member spaced from each of said end walls and having a plurality of slots therein arranged in a substantially circular formation, a plurality of columns extending between said end walls and each having the opposite end portions thereof engaged in similarly positioned slots of the respective cushioning

members, said columns being arranged to extend through the spaces formed between the spider arms of said lamp shades, and each having similarly positioned means spaced therealong for engaging a spider arm whereby a plurality of said lamp shades may be nested within said enclosing body with the respective spiders thereof spaced one from the other.

7. In a package for lamp shades, each having radial spider arms, an enclosing box body having end walls, a cushioning member adjacent each end wall and having means maintaining same in spaced relation to said wall, a plurality of slots circularly arranged in each of said cushioning members, a plurality of rigid columns engaging through said slots and having the opposing ends thereof bearing against the respective end walls, means provided upon each of said columns intermediate the ends thereof engaging the spider arm of a lamp shade at spaced levels, whereby a plurality of such shades may be supported from said columns, nested one within the other within said body.

8. In a package for lamp shades, each having radial spider arms, an enclosing box body having end walls, a cushioning member adjacent each end wall and having means maintaining same in spaced relation to said wall, a plurality of slots circularly arranged in each of said cushioning members, a plurality of rigid columns engaging through said slots and having the opposing ends thereof bearing against the respective end walls, means provided upon each of said columns intermediate the ends thereof engaging the spider arm of a lamp shade at spaced levels, whereby a plurality of such shades may be supported from said columns, nested one within the other within said body, said means including slots within which said spider arms are adapted to be inserted.

9. In a package for lamp shades, each having

radial spider arms, an enclosing box body having end walls, a cushioning member adjacent each end wall and having means maintaining same in spaced relation to said wall, a plurality of slots circularly arranged in each of said cushioning members, a plurality of rigid columns engaging through said slots and having the opposing ends thereof bearing against the respective end walls, means provided upon each of said columns intermediate the ends thereof engaging the spider arm of a lamp shade at spaced levels, whereby a plurality of such shades may be supported from said columns, nested one within the other within said body, said means including slots within which said spider arms are adapted to be inserted, and means closing off the slots to prevent withdrawal of said arms.

10. In a package for lamp shades, each having radial spider arms, an enclosing box body having end walls, a cushioning member adjacent each end wall and having means maintaining same in spaced relation to said wall, a plurality of slots circularly arranged in each of said cushioning members, a plurality of rigid columns engaging through said slots and having the opposing ends thereof bearing against the respective end walls, means provided upon each of said columns intermediate the ends thereof engaging the spider arm of a lamp shade at spaced levels, whereby a plurality of such shades may be supported from said columns, nested one within the other within said body, said columns each having a substantially V-shaped cross section pointed in substantially the same circular direction, and extending through the spaces between said spider arms and said last mentioned means comprising transverse slots in the apex of each column whereby a shade disposed in the box body may be arranged adjacent said slots and rotated, moving its spider arms into a slot of each column on any given level.

DAVID J. GORELICK.
